UNITED STATES PATENT OFFICE.

CLARENCE R. SHAW, OF MARINE CITY, MICHIGAN.

HEATING SYSTEM.

1,167,528.

Specification of Letters Patent. Patented Jan. 11, 1916.

Application filed March 13, 1915. Serial No. 14,270.

To all whom it may concern:

Be it known that I, CLARENCE R. SHAW, a citizen of the United States, residing at Marine City, in the county of St. Clair and State of Michigan, have invented certain new and useful Improvements in Heating Systems, of which the following is a specification, reference being had to the accompanying drawings.

10 This invention relates to certain improvements in heating systems and has relation more particularly to a steam vacuum heating system and it is an object of the invention to provide a system of this general character having novel and improved means whereby after radiation, the air line is automatically sealed.

It is also an object of the invention to provide a system of this general character 20 having novel and improved means whereby the air line is automatically sealed upon the lowering of the steam pressure whereby air is prevented from reentering the system.

It is also an object of my invention to 25 provide a novel and improved system of this general character including a condensation tank provided with means whereby said condensation may be automatically returned to the boiler and whereby the system 30 is effectively sealed during the period such condensation is being returned.

It is also a further object of my invention to provide an improved system of this general character including a condensation tank 35 which may be readily removed or taken down, without effecting the operation of the system.

My invention also contemplates the use of novel and improved air controlled means 40 adapted to coact with a radiator.

The invention consists in the details of construction and in the combination and arrangement of the several parts of my improved heating system, whereby certain important advantages are attained and the device is rendered simpler, less expensive and otherwise more convenient and advantageous for use, all as will be hereinafter more fully set forth.

50 The novel features of the invention will be carefully defined in the appended claims.

In order that my invention may be the better understood, I will now proceed to describe the same with reference to the accompanying drawings, wherein is disclosed a diagrammatic view illustrating a system

arranged in accordance with an embodiment of my invention, the condensation tank and its concomitant parts being shown on an enlarged scale and partly in elevation 60 and partly in section.

As disclosed in the accompanying drawings, B denotes a boiler of conventional construction, R a radiator, S a steam pipe and P a return pipe, said return pipe having in 65 connection therewith a condensation tank T positioned at a point at least twelve inches above the water line of the boiler and through which substantially all of the water of condensation is adapted to flow. 70 Tank T, as herein embodied is of elongated shape, having one end extremity in communication with the return pipe P through the medium of the branch pipe 1, having interposed therein a conventional gate valve 75 2, the return pipe P, at a point intermediate its communication with the branch pipe 1 and with the boiler being provided with the spaced conventional globe valves 3 and 4 and having interposed therein at a 80 predetermined point between the valves 3 and 4, the check valve 5, whereby upward pressure through the return pipe, is prevented.

Telescopically engaged with the branch 85 pipe 1 and projecting through a head of the tank T is an extension 6 of the casing 7 positioned within the tank, said casing having mounted therein the valve 8' adapted to coact with the adjacent extremity of the 90 branch 1 for sealing the same. The outer extremity of the extension 6 is provided with the stuffing box 9 whereby a sealed connection is assured between the branch 1 and the extension 6 and in order to maintain the extension 6 against movement independently of the branch 1, I find it of advantage to dispose therethrough the set screw 10 adapted to clampingly engage the branch 1. I also find it of advantage to have coacting with the extension 2 a conventional 100 jam nut 11 coacting with the outer face of the adjacent head of the tank T for further maintaining the extension in its adjustment.

In communication with the lower portion 105 of the casing 7 is a conduit 12 extending longitudinally of the tank T and terminating in the depending portion 14 disposed within the well 15 produced in the tank adjacent the opposite extremity thereof.

Positioned within the well 15 is a float 16 110 adapted to engage beneath an extremity of

the rod 17 fixed to a bell lever 18 pivotally mounted, as at 19, within the tank T and having one extremity operatively engaged with the endwise movable rod 20 for the 5 valve 8 whereby it will be perceived that upward movement of the float 16 will cause the valve 8 to seat against the adjacent extremity of the branch 1 and thus seal the system against the steam pressure. It will 10 be perceived that the relative endwise adjustment of the extension 6 relative to the branch 1 will determine the extent of upward movement required and the float 16 causing the valve 8 to assume a closed position. 15

In communication with the tank T at a point above the well 15 is the relief valve 21 in communication with the atmosphere, said valve including the seats 22 and 23, the uppermost seat 22 having coacting therewith the ball valve 24 while the lower valve seat 23 has coacting therewith the valve member 25 fixed to the stem 26 adapted for vertical movement and projecting within the 20 valve 21, the upper extremity of the stem 26 being arranged for contact with the valve 24 for unseating the same upon upward movement of the stem and at a predetermined period before the valve 25 operatively 25 engages the lower valve seat 23. The lower extremity of the stem has mounted thereon a grooved wheel 27 operatively engaging the spring track-way 28 carried by the float 16 and serving to compensate 30 for any deficiency in the event the valves 8 and 25 should not work in strict accord. As is believed to be self-evident, condensation is collected within the well 15 which results in the elevation of the float 16 whereupon 35 the valve 24 is unseated and permits ingress within the tank T of atmospheric pressure to cause the condensation to be automatically discharged through the siphon 29 carried by the removable head 30 of the tank T and having its inner extremity terminating adjacent the bottom of the well 15 and with its opposite extremity in communication with the branch return pipe 31 40 extending below the tank 1 and in suitable communication with the return pipe P, whereby it will be perceived that such condensation will be returned to the boiler B. 45

As hereinbefore stated, the upward movement of the float 16 will cause the valve 8 to seat against the adjacent extremity of the branch pipe 1 and thus seal the system against steam pressure so that the atmospheric pressure will be sufficient to force the water of condensation through the siphon 50 29 and pipe 31.

In communication with the branch return pipe 31 and the well 15 is an equalizing pipe 32 and interposed within the branch return pipe 31 at a point intermediate the equalizing pipe 32 and the siphon 30

is the check valve 33 which serves to prevent retrograde flow through the siphon. I also find it of advantage to interpose in the equalizing pipe 32 a conventional globe valve 34. The well 15 has also in communication therewith and depending therefrom the pet cock 35 of any ordinary or preferred construction. 70

In communication with the radiator R at the conventional point thereon is the controlling valve V in communication with the return pipe P through the branch pipe 36. 75

From the foregoing description, it is thought to be obvious that a heating system constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice. 80 85 90

I claim:

1. A system of the character described including, in combination with a boiler, a steam pipe and a return pipe, a tank positioned above the water-line of the boiler and in communication with the return pipe, said tank having a well portion formed in one end thereof, a valve within the tank for controlling the communication with the return pipe, a conduit leading from the return pipe into the well, a float within the well and having connection with the valve for automatically operating the same, a relief valve in communication with the tank, said relief valve being under control of the float, a siphon in communication with the well and with the return pipe, and a check valve interposed in the siphon and serving to prevent retrograde flow therethrough. 95 100 105 110

2. A system of the character described including, in combination with a steam pipe and a return pipe, a tank, said tank having a well formed in one end thereof, a branch pipe in communication with the return pipe and projecting with the tank, a casing telescopically engageable with the return pipe and extending within the tank, a conduit leading from the casing into the well, the inner extremity of said branch pipe serving as a valve seat, a valve mounted for reciprocal movement within the casing and coacting with the valve seat, a float positioned with in the tank, an operative connection between the float and the valve whereby said valve is moved upon the raising or falling of the float, a relief valve in communication with the tank, means under control of the float 115 120 125 130 135 140

for operating the relief valve, said last named means being capable of limited independent operation, a siphon in communication with the well and return pipe, and a 5 check valve interposed in the siphon and serving to prevent retrograde flow therethrough.

3. A system of the character described including, in combination with a boiler, a 10 steam pipe and a return pipe, a tank positioned above the water-line of the boiler and in communication with the return pipe, a valve within the tank for controlling the communication with the return pipe, a float 15 within the tank and having connection with the valve for automatically operating the same, a relief valve in communication with the tank, spaced seats therein, a ball valve coacting with the uppermost seat, a 20 stem movable vertically within said valve, a second valve member carried by the stem and coacting with the lowermost valve seat, the upper extremity of said stem being arranged for contact with the ball valve to 25 unseat upon upward movement of the stem and at a predetermined period before the second valve operatively engages the lower valve seat, and means carried by the float

for yieldingly engaging the lower extremity of the stem as and for the purpose set forth. 30

4. A system of the character described including, in combination with a steam pipe and a return pipe, a tank, a branch pipe in communication with the return pipe and projecting within the tank, a casing telescopically engageable with the return pipe and extending within the tank, the inner extremity of the branch serving as a valve seat, a valve mounted for reciprocal movement within the casing and coacting with 40 the valve seat, a float positioned within the tank, an operative connection between the float and the valve whereby said valve is moved upon the raising or falling of the float, a relief valve in communication with 45 the tank, and means under control of the float for operating the relief valve, said last named means being capable of limited independent operation.

In testimony whereof I hereunto affix my 50 signature in the presence of two witnesses.

CLARENCE R. SHAW.
